UNITED STATES PATENT OFFICE

2,409,495

TABLE

Charles F. Kelley, Chicago, Ill.

Application May 10, 1943, Serial No. 486,311

1 Claim. (Cl. 311—26)

1

This invention relates to a table and particularly to a table of a type suitable for use in bed. It has for one object to provide a table which is strong and simple in construction which may be made entirely of wood and which can be positioned over a bed and supported upon the bed structure itself.

Another object is to provide a table of the type indicated, so arranged that many such tables can be stacked or "nested" together.

Another object is to provide a table of the type indicated which can be readily put in place over and upon a bed while the bed is occupied, and which will be readily retained in place upon the bed either by latching means or by the bed spring or mattress itself.

A still further object is to provide a bed table so arranged that it can be supported upon the structural members of the bed rather than upon the floor.

Other objects will appear from time to time throughout the specification and claim.

This invention is illustrated more or less diagrammatically in the accompanying drawings, wherein:

Figure 1 is a side elevation of one form of the table;

Figure 2 is an end elevation of Figure 1;

Figure 3 is a plan view;

Figure 4 is a vertical sectional detail taken on an enlarged scale at line 4—4 of Figure 2;

Figure 5 is an isometric projection of the table shown in Figures 1 to 3, inclusive;

Figure 6 is a side elevation of a modified form of table; and

Figure 7 is an end elevation of the table shown in Figure 6.

Like parts are indicated by like characters throughout the specification and the drawings.

1 is the top of a table. 2 is a fixed leg secured to the table top. A member 3 may, if desired, be added to strengthen the joint. 4 is an attaching member fixed to the table top, and the joint may be strengthened by a member 5, if desired. It will be noticed, particularly in Figure 4, that the lower edge of the member 4 is inclined or beveled, as at 6. Attached by hinges 7 or otherwise to the member 4 is a second leg 8.

The tables of the two forms are identical up to the point so far described. Each table is provided with means for engaging a rail or other structural part of the bed. In the form of the table shown in the first five figures, a flange or shelf-like member 9 is secured adjacent the lower edge of the leg 2 and the leg 8. This flange

5 may rest upon the bed rail 10 or some other structural part of the bed. As shown, a spring 11 may be secured to the rails 10, and a mattress 12 may be positioned on the spring. The flange or shelf members rest upon the rails 10 or upon the upper surface of the spring 11 and extend somewhat beneath the mattress 12, provided one is present.

10 As a means for holding the movable leg 8 in place, a latch assembly is provided. This includes a member 13, secured as shown in Figures 1, 2, 3 and 5, to the inner surface of the movable leg 8. The member 13 is provided with a cavity or cut away portion 14. A movable latch member 15 is hinged, as at 16, to the bottom of the table portion 1. As shown, the latch member 15 may be reduced in size adjacent its lower end and provided with a nose 17, which in the latching position extends into the cut away portion 14 of the 15 member 13. When the latch is in the position shown in the figures, it prevents swinging of the movable leg 8 and holds it in the full line position of Figure 1.

16 In the modified form of Figure 6, the table leg, 25 instead of carrying flange or shelf-like members 9, is provided with portions 18 and 19 adjacent the lower ends of each of the legs 2 and 8. The members 18 and 19 form, together with the lower edges of the legs 2 and 8, trough-like members 30 which fit over and engage the bed rails 20 or corresponding structural members of the bed.

35 The particular forms shown in Figures 6 and 7 are adapted primarily for use with a bed in which the spring and mattress are positioned above the rails. As shown, therefore, in those figures, a spring 21 is positioned above the rails 20 and may carry a mattress 22.

The use and operation of this invention are as follows:

40 When the tables are not in use, the movable legs are swung to the dotted line position of Figures 1 and 6, and then the tables may be piled, stacked, or "nested" together, the top portion of each table fitting beneath and against the folded, 45 movable leg 8 of the table adjacent it. When the tables are to be put into use, they are separated one from the other and placed in position over the bed. If the form of Figure 1 is to be used, the table is placed over a bed, the left-hand flange 9 50 engaging the rail 10 or upper surface of the spring 11, and the movable leg 8 being moved to the outer or right-hand dotted line position. This permits the table to clear the bed and mattress. When that has been done, the movable leg is 55 moved to the full line position of Figure 1 and

the latch means is moved so that the latch engages the member 13, and the table is held in place. Under certain conditions the latch mechanism may be omitted, and the mattress itself will hold the table in place.

When the form of Figure 6 is to be used, substantially the same steps are taken in putting it into place. The left-hand leg 2 is moved to the position of Figure 6, and its trough-like member fits over and engages the bed rail at that side. The right-hand leg is swung to the outer or right-hand dotted line section, and the table may thus be placed over the bed. When the left-hand leg is in position on the rail, the right-hand leg is moved so that its trough engages the right-hand bed rail. Although a latch mechanism might be used with the form of Figures 6 and 7, it is ordinarily not needed, first, because the trough-like construction itself firmly engages the bed rails, and second, because ordinarily the mattress 22, under the weight of an occupant will expand sufficiently to exert a pressure on the table legs and to force them against the bed rails so that even without a latching mechanism the table will ordinarily remain in place.

Although I have shown an operative form of my invention, it will be recognized that many changes in the form, shape, and arrangement of parts can be made without departing from the

spirit of the invention, and my showing is therefore to be taken as, in a sense, diagrammatic. In particular, it is to be understood that the invention is not limited to any particular material.

5 It can be made all of wood or it can be made of any other desirable material. Although the table is shown as engaging the bed rails, it can, of course, be held in place by engaging any other structural part of the bed, and the invention is not limited in its use, therefore, to the specific engagement of parts of the table with bed rails or with any specific structural member of a bed.

I claim:

15 In combination in a table adapted for use with and to be supported upon a bed, members defining a table surface member, and a leg fixed thereto, a downwardly projecting support fixed on the opposite end of said surface member, and a movable leg movably supported from said surface member by said support, and bed rail engaging members mounted one on each of said legs and adapted to engage a bed, the width of said bed rail engaging members being approximately the same as the length of the said support, whereby when the movable leg is folded against the table surface member it is substantially parallel therewith.

CHARLES F. KELLEY.
